ATTORNEY

UNITED STATES PATENT OFFICE

GUY M. FRENCH, OF RENFREW, ONTARIO, CANADA

DOOR OPERATING MEANS

Application filed December 22, 1930. Serial No. 503,991.

This invention relates to door operating mechanism and has for its principal object the provision of means whereby double doors, such as garage doors, may be swung simultaneously to open or closed position.

Another object is the provision of means whereby the operating mechanism may be actuated from a distance.

Another object is the provision of means whereby certain mechanism is operated to trip a tension spring which, when moved to a predetermined position, will actuate the door operating mechanism.

With these and other objects in view as will appear as the description proceeds, the invention consists of the novel construction, combination and arrangement of co-operating elements as hereinafter more specifically set forth, claimed and shown in the accompanying drawings forming a part of the present application, in which:

Fig. 1 is a top plan view of the preferred embodiments of my invention, the same being taken on a plane just below the ceiling of a garage.

Fig. 2 is a sectional view taken on the line 2-2 of Fig. 1 the ceiling and roof being shown in this view.

Fig. 3 is a similar view to Fig. 1, disclosing a modified form of my invention.

Like numerals of reference designate corresponding parts throughout the different views.

3 is a guide bar reciprocally mounted in suitable guide brackets 4, which guide brackets are secured to the ceiling of the garage or a suitable platform 5. Secured to the top and bottom faces of the guide bar 3 are U-brackets 6 and 7. Extending through the U-brackets 6 and 7 and guide bar 3 is a bolt 8, which is headed at one end and provided with a lock-nut 9. Pivotally attached at one end to the bolt 8, between the U-bracket 7 and the guide bar 3, are connecting rods 10 and 11. The opposite ends of the connecting rods 10 and 11 respectively, are pivotally supported in bearing brackets 12 and 14 secured to the inner face of the garage doors 15 and 16, in spaced relationship from the hinges 17 and 18 respectively. The connecting rods 10 and

11 are preferably offset intermediate their ends as at 19 and 20 so that the outer ends thereof may be conveniently attached to the doors 15 and 16 respectively. 21 is a lever arm pivotally connected at one end to a bolt 22, extending downwardly from and secured to the ceiling or platform 5. The opposite end of the lever arm 21 is forked as at 23, the free ends of the prongs 23a and 23b of the fork 23 converging towards each other. The prongs of the fork 23 straddle the bolt 8 between the U-brackets 6 and the guide bar 3. 24 is an operating lever pivotally connected at one end to the bolt 22 and supported at its free end by the guide bracket 25, which guide bracket is secured to the ceiling or platform 5. 26 are spaced apertures formed through the lever arm 21. 27 is a bolt or stud extending through one of the apertures 26 and secured therein by the lock-nut 28. 29 are spaced apertures formed in the operating lever 24. 30 is a bolt or stud extending through one of the apertures 26 and secured therein by the lock-nut 31. 32 is a tension spring, one end of which is connected to the bolt or stud 27 while the opposite end thereof is secured to the bolt or stud 30. The bolts 27 and 30 may be replaced in the apertures 26 and 29 inwardly or outwardly relative to each other to diminish or increase the tension of the spring 32. 33 is a flexible member connected at one end to the free end of the operating lever 24. The flexible member 33 is trained over the pulley 34, extended out through an aperture 35, formed in the front wall of the garage, and thence extended to a predetermined location. 36 is a flexible member attached at one end to the free end of the operating lever 24. The flexible member 36 extends through the opening 35 and to a point adjacent the free end of the flexible member 33. Attached to the free end of the flexible member 33 is a suitable ring or handle 37. Attached to the free end of the flexible member 36 is a suitable ring or handle 38. Suitable pulleys 39 and 40 may be provided, over which the free ends of the flexible members 33 and 36 respectively may be trained and suspended.

Referring to Fig. 1, it will be noted that the

operating lever 24 is retained in angular relationship to the lever arm 21 by means of the tension spring 32 which spring, through the mediums of the guide bracket 25, bolt 8, guide bar 3 and connecting rods 10 and 11, will retain the doors 15 and 16 in closed position. If desirous of opening the doors 15 and 16, the operator will grasp the ring 37 and, upon pulling the same, will cause the flexible member 36 to pivot the operating lever 24 from the position as shown in full lines to the position as shown in dotted lines. When the operating lever 24 is pivoted to the position as shown in dotted lines, the tension spring 32 will be pivoted across under the bolt 22 to a position represented by the dotted line 41 and the tension of the spring 32 exerted between the bolt 30 and the bolt 27 will cause the lever arm 21 to pivot on the bolt 22 from the position as shown in full lines to the position as shown in dotted lines. As the lever arm 21 commences to move, the prong 23a will sharply contact with the bolt 8 and transmit movement thereto, and consequently, to the guide bar 3 in a forward direction. The impetus thus given to the guide bar 3 will be transmitted through the connecting rods 10 and 11 to overcome any primary friction in the connections and, if the device is being operated in the winter, will cause any accumulation of ice or the like to be dislodged. As the lever arm 21 continues to move from the position as shown in full lines to the position as shown in dotted lines, guide bar 3, connecting rods 10 and 11 and doors 15 and 16 will be moved from the position as shown in full lines to the position as shown in dotted lines and will be retained in such position by the tension spring 32.

When it is desirous of closing the doors 15 and 16, the ring 37 will be pulled and, through the medium of the flexible member 33, will pivot the operating lever 24 from the position shown in dotted lines to the position as shown in full lines. As the operating lever 24 is thus pivoted, the tension spring 32 will be pivoted across under the bolt 22 to the position indicated by the dotted line 42 and the tension of the spring 32 between the bolt 30 and the bolt 27 will cause the lever arm 21 to pivot from the position as shown in dotted lines to the position as shown in full lines. As movement is thus transmitted to the lever arm 21, the prong 23b will sharply contact with the bolt 8. As the lever arm 21 continues to move from the position as shown in dotted lines to the position as shown in full lines, guide bar 3, connecting rods 10 and 11 and doors 15 and 16 will be moved from the position as shown in dotted lines to the position as shown in full lines, and will be retained in such position by the tension spring 32.

Referring to the modified form of my invention as disclosed in Fig. 3, I dispense with

the guide bar 3 and guide brackets 4 and connect the connecting rods 10a and 11a to angularly disposed arms 21a and 21b of the bell-crank 21c. In this modified form of my invention the tension spring 32a is connected between the bolts 30a and 27a carried by the operating lever 24a and arms 21b respectively. 33a is a flexible member connected at one end to the free end of the operating lever 24a. The flexible member 33a is trained around the pulley 34a, around the pulley 34b, through the opening 35a and is extended in a similar manner to the flexible member 33 as disclosed in Fig. 1. 36a is a flexible member attached to one end of the free end of the operating lever 24a. The flexible member 36a is trained over the pulley 34c through the opening 35a and is extended in a similar manner to the flexible member 36 as disclosed in Fig. 1.

When it is desirous of opening the doors 15a and 16a, the flexible member 36a is pulled, causing the operating lever 24a to be pivoted from the position as shown in full lines to the position as shown in dotted lines. As the operating lever 24a is thus moved, the tension spring 32a will be pivoted across under the bolt 22a to the position represented by the dotted line 41a and the tension of the spring 32a between the bolts 30a and 27a will cause the arms 21b and 21a to pivot on the bolt 22a from the position as shown in full lines to the position as shown in dotted lines. As the arms 21b and 21a are thus moved, the connecting rods 10a and 11a will be moved from the position as shown in full lines to the position as shown in dotted lines and through the medium of the bearing brackets 12a and 14a will cause the doors 15a and 16a to swing from closed position as shown in full lines to open position as shown in dotted lines.

When it is desirous of closing the doors 15a and 16a, the flexible member 33a will be pulled to pivot the operating lever 24a from the position as shown in dotted lines to the position as shown in full lines and the tension spring 32a will be pivoted across under the bolt 22 to the position designated by the dotted line 42a. The tension spring 32a, through the mediums of the bolts 27a and 30a will cause the arms 21b and 21a to move from the position as shown in dotted lines to the position as shown in full lines and through the medium of the connecting rods 10a and 11a will cause the doors 15a and 16a to swing from the position as shown in dotted lines to the position as shown in full lines.

The foregoing specification and annexed drawings disclose the preferred embodiment of my invention, but it is to be understood that minor changes may be resorted to in the commercial adaptation of my invention without departing from the scope of the invention as hereinafter claimed.

What I claim as new is:

1. Mechanism for operating doors comprising connecting rods, one end of each connected to one of said doors respectively; a lever arm, to which the other ends of said rods are operatively connected; a tension spring, one end of which is connected to said lever arm; an operating lever, to which the other end of said tension spring is connected, 10 said operating lever being pivotally mounted in such a manner as to pivotally move said tension spring to an angular position at opposite sides of said lever arm, upon movement of said operating lever in opposite directions; means for moving said operating lever in opposite directions and said spring adapted to tensionally pivot said lever arm to cause said doors to open or close according to the direction of movement of said operating lever. 15
2. Mechanism for operating doors comprising connecting rods, one end of each connected to one of said doors respectively; a lever arm, to which the other ends of said rods are operatively connected; a tension spring, one end of which is connected to said lever arm intermediate the ends thereof; an operating lever, to which the other end of said tension spring is connected intermediate the ends thereof, said operating lever being pivotally mounted in such a manner as to pivotally move said tension spring to an angular position at opposite sides of said lever arm, upon movement of said operating lever in opposite directions; means for moving said operating lever in opposite directions and said spring adapted to tensionally pivot said lever arm to cause said doors to open or close according to the direction of movement of said operating lever. 20
3. Mechanism for operating doors comprising connecting rods, one end of each connected to one of said doors respectively; a lever arm, to which the other ends of said rods are operatively connected; a tension spring, one end of which is connected to said lever arm; an operating lever, to which the other end of said tension spring is connected; means for pivoting said operating lever and 25 said tension spring to respective angular positions at opposite sides of said lever arm; and said spring adapted to tensionally pivot said lever arm to cause said doors to open or close according to the direction of movement of said operating lever. 30
4. Mechanism for operating doors comprising guide brackets; a guide bar reciprocally mounted in said guide brackets; a bolt carried by said guide bar; connecting rods pivotally connected at one end to said bolt and at their opposite ends to said doors respectively; a lever arm pivotally secured at one end; a fork formed on the free end of said lever arm, the prongs of said fork straddling 35 said bolt; an operating lever pivotally se- 40
- cured at one end; a tension spring connected at one end to said lever arm and at its opposite end to said operating lever; means for pivotally moving said operating lever in such a manner as to pivotally move said tension 45 spring to an angular position at opposite sides of said lever arm, upon movement of said operating lever in opposite directions. 50
- In testimony whereof, I affix my signature.
